UNITED STATES PATENT OFFICE.

JACOB W. LATTIG, OF GLENSIDE, PENNSYLVANIA, AND CHARLES L. GOODRUM, OF NEW YORK, N. Y., ASSIGNORS TO WESTERN ELECTRIC COMPANY, INCORPORATED, OF NEW YORK, N. Y., A CORPORATION OF NEW YORK.

AUTOMATIC TELEPHONE SYSTEM.

1,251,543.

Specification of Letters Patent.

Patented Jan. 1, 1918.

Application filed April 25, 1916. Serial No. 93,385.

To all whom it may concern:

Be it known that we, JACOB W. LATTIG and CHARLES L. GOODRUM, citizens of the United States, residing at Glenside, in the 5 county of Montgomery and State of Pennsylvania, and at New York, in the county of New York and State of New York, respectively, have invented certain new and useful Improvements in Automatic Telephone 10 Systems, of which the following is a full, clear, concise, and exact description.

This invention relates to automatic telephone systems, and more particularly to a system in which a calling subscriber can 15 hold a connection which has been connected to a busy line, the talking strands of which are maintained open, and be automatically connected to said line for conversation when it becomes idle.

20 The object of the invention is to provide means to hold connections when they have been switched to a busy line in which the talking strands are maintained open, and to automatically establish the conversational 25 circuit with but one of said calling lines when said called line becomes idle.

The invention is illustrated in the accompanying figure which shows in diagrammatical form a connection between two subscribers, the circuits of the connector being 30 shown in detail.

In the embodiment of the invention shown in the figure, the invention is associated with a two-wire automatic system, but it will be 35 understood that it may be readily applied to any one of the well-known types of automatic systems.

In the system illustrated, when the calling subscriber removes his receiver from the 40 hook, the line finder 4, shown diagrammatically in the figure, will be switched to the contacts of the calling subscriber's line. When the calling subscriber's line has been connected through to the line finder, he will 45 operate his impulse transmitter and thereby send a series of impulses to connect the movable contacts of the first selector 5, diagrammatically shown, with the terminals of a trunk leading to a connector containing

the terminals of the desired called subscriber's line. 50

When the calling subscriber has been connected to the connector, he will send a second series of impulses over the line to select the group of contacts of the connector switch 55 which contains the terminals of the desired called line. Immediately upon being connected to the trunk terminals leading to the connector, the line relay 6 will be operated and the operation of this relay completes a 60 circuit from the ground at its armature by way of its make contact and the slow acting relay 7 to battery. Consequently, when the calling subscriber sends the series of impulses to select the desired group of contacts 65 in the connector, the armature of line relay 6 will vibrate and will close a circuit from the ground at its armature by way of its break contact, the right hand armature and make contact of relay 7 and the slow acting 70 relay 8 to battery. This last circuit contains a parallel branch which may be traced from the right hand armature and make contacts of relay 7 by way of the break contact and armature of relay 9, the side switch arm 75 11 and the primary magnet 12 to battery. The operation of the primary magnet 12 will set the movable contacts 14 of the connector switch in alignment with the group of contacts of the contact bank of the connector 80 which contain the terminals of the desired line. The operation of the slow relay 8 will close a circuit from the ground at the armature and make contact of relay 7 by way of the make contact and armature of relay 8, 85 side switch arm 15 and the side switch escape magnet 16 to battery.

After the subscriber has transmitted the first set of impulses to the connector, the line relay 6 will again be permanently operated for a definite period, and this will open the circuit of the slow acting relay 8 which will therefore be deenergized. The deenergization of the slow acting relay 8 opens the circuit of the escape magnet 16 90 and this will move the side switch of the connector into its second position. 95

The calling subscriber will now send a

second series of impulses which will again vibrate the line relay 6, and since the side switch arm 11 is in its second position, the secondary magnet of the connector switch 5 will be operated to move the contacts 14 of the connector switch to the terminals of the desired line. When the movable contacts 14 connect with the terminals of the desired line, which will be assumed to be busy, a 10 circuit will be established from the ground existing on the test conductor, by virtue of the line previously connected to the multiple contacts of this line, through the test wiper of the movable contacts 14, the side switch 15 arm 20 and the right hand winding of the test relay 9 to battery. This will cause the energization of the test relay 9 which will complete a locking circuit for itself by way of ground, its left hand winding, make contact and armature of the relay and the brush and one disk of the interrupter 21 to battery. The operation of the test relay 9 will likewise close a circuit from the ground at its middle left hand armature, the make contact, side switch arm 15 and the escape magnet 16 to battery. This circuit will cause the continued energization of the escape magnet 16, and consequently prevent the movement 20 of the side switch arms of the connector 25 switch into the third position.

In this second position of the side switch, a busy tone will be sent to the calling subscriber by means of a circuit which may be traced from ground through winding 24 of 30 the transformer, side switch arm 25, off-normal contact 26 of the connector switch to the lower side of the calling subscriber's line, through the subscriber's loop and back over the upper side of the subscriber's line 35 and the coil 27 to battery and ground. This busy signal will inform the calling subscriber that the line desired is busy and the subscriber may then at his option either hang up and release the connection, or wait 40 at his telephone until the desired subscriber's line becomes idle, at which time his line will be automatically switched into connection with the desired line.

It will be assumed that the calling subscriber is holding the connection until the desired called subscriber's line becomes idle. In this case, when the called line becomes idle the ground will be removed from the 45 multiple test conductor and this will open 50 the energizing circuit of the right hand winding of the test relay 9. It will be remembered, however, that this test relay in operating closes for itself a locking circuit by way of its armature and one disk of the 55 interrupting device 21. The interrupting device 21 consists of a constantly rotating shaft on which are mounted a series of metallic disks, each one of which is equipped 60 in its periphery with an insulated segment.

These insulated segments in the various disks 65 are angularly displaced around the circumference so that the insulated portion of the disk assigned to any particular connector switch will contact with its corresponding wiper brush at a time when the brushes of 70 all the other disks are connected to the metallic portion of the disk. Consequently, when the energizing circuit of the right hand winding of the test relay 9 is opened, this relay is retained in its operated position by the circuit completed through one 75 of the disks of the interrupter 21 and when the brush allotted to the particular connector rides on the insulated portion of its associated disk this circuit will likewise be 80 opened and the test relay will be deenergized.

The deenergization of the test relay 9 will open the circuit of the escape magnet 16 at its middle left hand armature, and consequently the arms of the side switch will move 85 into their third position. In the third position of the side switch a circuit is completed for the escape magnet 16 from battery through its operating winding, side switch arm 15, the armature and break contact of 90 ringing relay 30 and the make contact and left hand armature of the slow acting relay 7 to ground. This circuit will hold the escape magnet of the side switch in its energized position and this circuit is controlled 95 by the armature of the ringing relay 30.

The operation of the escape magnet 16 closes a circuit from the generator 31 through the winding of the ringing relay 30, the armature and make contact of the 100 escape magnet 16, side switch arm 32, the lower side of the trunk and thence by way of the lower side of the line through the called subscriber's loop and back over the upper side of the line and trunk and side 105 switch arm 33 to ground. This will apply ringing current to the called subscriber's line and when the subscriber answers, the flow of current through the called subscriber's loop will increase sufficiently to energize the ringing relay 30, which in energizing will open the energizing circuit of the escape magnet 16, which in turn will cause the movement 110 of the side switch arms into the fourth position, thereby completing the conversational 115 circuit from the calling to the called subscribers.

When the subscribers have completed their conversation they will hang up their receivers. The calling subscriber in hanging up his receiver will open the circuit of the line relay 6, and this will close a circuit from the ground at its armature by way of the break contact, the right hand armature and break contact of relay 7 and through the off-normal contact 35 and the release magnet 36 to battery. This will energize the release magnet 36 of the connector switch 120 125

and restore this switch to its normal position. In a like manner, the apparatus at the first selector and finder will also be restored. The circuits to the release magnets of the 5 first selector and finder are similar to those shown in an application by C. L. Goodrum, Serial No. 872,743, filed November 18, 1914.

The circuits of the figure show three test relays multiply connected to the test wire of 10 the called line when the test brush contacts with its associated test contact, and it will be obvious that all the test relays of the connectors of a group will be connected in a like manner. Each of these test relays is 15 provided with a locking winding, one terminal of which is connected to ground and the other is wired through a disk of the interrupter 21. Therefore, as these disks are all equipped with insulated segments which are 20 angularly displaced with respect to one another in the circumference of the disks, the locking circuits of the various test relays will be opened, one at a time in succession, as the brush allotted to each disk comes in 25 contact with the insulated segment. It will therefore be obvious if several subscribers attempt to call a line which is busy and they all hold the connection so as to be switched into circuit when the called subscriber's line 30 becomes idle, but one of these subscribers can be connected to the called subscriber's line at a time. This follows from the fact that the movement of the side switch arms into the third position is controlled by a 35 make contact on the test relay 9 and the side switch will therefore not move into its third position until the test relay 9 is deenergized.

Further, since the test relay is locked by means of its left hand winding by a circuit 40 wired through one disk of the interrupter, the test relays of all the calling lines connected to a busy called subscriber's line that has been rendered idle, will be energized through these locking windings. Since these 45 locking windings of the various test relays will be opened one at a time in succession due to the angular displacement of the insulated portions in the disks of the interrupter, but one subscriber can be connected at a 50 time to the terminals of the desired called line.

As has been previously stated the interrupter 21 is provided with a series of disks equal in number to the connector switches 55 contained in a group, and the connectors of the various groups are wired in multiple to the brushes coöperating with these disks. This multiple connection from the various groups of connectors to the brushes coöperating with the disks of the interrupter 21 60 will not result in double connections since a different series of subscribers' lines are multiply connected to the contact terminals of each group of connector switches.

Obviously the invention is not limited to 65 the specific embodiment herein shown and described, but is capable of many variations and applications without departing from its spirit and scope.

What is claimed is:

1. In an automatic telephone system, the combination with a plurality of calling subscribers' lines, of engaged subscribers' lines, means to switch said calling lines to the terminals of an engaged subscriber's line, 75 means to maintain the conversational circuits of said lines to said busy subscriber's line open when so connected, and means when said called subscriber's line becomes idle to automatically complete the conversational circuit of one only of said plurality of calling subscribers' lines to said called subscriber's line. 80

2. In an automatic telephone system, the combination with a plurality of calling subscribers' lines, of engaged subscribers' lines, means to switch said calling lines to the terminals of an engaged subscriber's line, 85 means to maintain the conversational circuit of said lines to said busy subscriber's line open when so connected, and means as said called subscriber's line becomes repeatedly idle to automatically complete in succession the conversational circuits from said plurality of calling subscribers' lines to 90 said called subscriber's line. 95

3. In an automatic telephone system, the combination with a plurality of calling subscribers' lines, of engaged subscribers' lines, means to switch said calling lines to the terminals of an engaged subscriber's line, 100 means to maintain the conversational circuit of said lines to said busy subscriber's line open, means to transmit a busy signal to said calling subscriber's line, and means when said called subscriber's line becomes idle to automatically complete the conversational circuit of one only of said plurality of calling lines to said called subscriber's line. 110

4. In an automatic telephone system, the combination with a plurality of calling subscribers' lines, of engaged subscribers' lines, means to switch said calling lines to the terminals of an engaged subscriber's line, test 115 relays operated to maintain the conversational circuit of said lines to said busy line open, and means to deenergize one only of said test relays when the called subscriber's line becomes idle to complete the conversational circuit of the associated calling line with said called subscriber's line. 120

5. In an automatic telephone system, the combination with a plurality of calling subscribers' lines, of busy subscribers' lines, 125 means to switch said lines to the terminals of a busy subscriber's line, relays for testing the condition of said called line and oper-

ated to prevent the closure of the conversa-
tional circuit of the calling line which has
been switched to the terminals of the busy
called line, and an interrupter for deener-
5 gizing one only of said relays when said
called line becomes idle to connect one of
said plurality of calling lines with said
called line.

In witness whereof, I hereunto subscribe
my name this 22nd day of April, A. D. 10
1916.

JACOB W. LATTIG.

In witness whereof, I hereunto subscribe
my name this 7th day of April, A. D. 1916.

CHARLES L. GOODRUM.
